UNITED STATES PATENT OFFICE.

LUCIUS E. TRUESDELL, OF BRISTOL, NEW HAMPSHIRE.

LOCOMOTIVE FIRE-EXTINGUISHING APPARATUS.

SPECIFICATION forming part of Letters Patent No. 380,956, dated April 10, 1888.

Application filed May 9, 1887. Serial No. 237,546. (No model.)

To all whom it may concern:

Be it known that I, LUCIUS E. TRUESDELL, a citizen of the United States, residing at Bristol, in the county of Grafton and State of New Hampshire, have invented certain new and useful Improvements in Locomotive Fire-Extinguishing Apparatus, of which the following is a specification.

The object of this invention is to provide a simple and sure means for an instantaneous discharge of steam from the boiler of a locomotive-engine directly into the fire-box for extinguishing the fire in time of collision or other similar accident; and the invention consists in connecting the fire-box with the boiler by means of suitable tubes and a valve or valves, and means whereby said valves are made to admit steam to the fire-box automatically at time of collision.

20 In the accompanying drawings, forming part of this specification, Figure 1 represents a sectional side elevation of a locomotive provided with my improved extinguisher, and Fig. 2 a detached sectional view of the attachment.

25 Similar letters represent corresponding parts.

A is the locomotive-boiler, and B its fire-box. A pipe, C, may tap the boiler either on its side or sides, or it may pass into its end 30 near the top and within the cab P.

Underneath the floor *p* of the cab P some suitable automatic valve may be placed, connecting the pipe C, coming from the boiler, with the pipe C', entering the fire-box. A 35 convenient form of valve is shown at D, in which the valve proper, *d*, and its valve-stem *d'* are closed by means of a toggle, the outer end of one of its arms, E, being connected by pivot either to said valve-stem or a casting, *d''*, 40 attached thereto, and the outer end of the other arm, E', to the bed-frame R of the locomotive.

A casting, F, uniting the arms E E' by means of pivot *f*, is provided with a socket, to which 45 is threaded a screw-shaft, G, having one end

rigidly secured within a suitable nut or head, *g*, which may be provided with holes *g'* in its sides for receiving a turn-pin or other convenient means for turning the same. This nut or head *g* rests upon a heavy movable block, H, 50 which is supported upon a bar, R', which may be attached to the frame R by stay rods or bars *r*. A packing-box, D', may be provided for the valve D.

The valve may be set up as tight as required 55 by turning the nut or head *g* and straightening the arms E E', and thus prevent the passage of steam from the pipe C to the pipe C', and in case of a sudden collision of the engine with another or a stationary object or car the 60 block H will slide off from the bar R', as indicated by dotted lines in Fig. 2, when the steam will immediately open the valve proper, *d*, and enter the fire-box B and extinguish the fire.

Having described my invention, what I claim, 65 and desire to secure by Letters Patent, is—

1. In a locomotive-engine, a steam pipe or pipes for conducting live steam from the boiler to the fire-box, a suitable valve for closing the passage for steam, and operating mechanism 70 whereby said valve may be automatically opened in case of accident, comprising a toggle and a movable supporting-block for same, all operating substantially for the purpose set forth.

2. In a locomotive-engine, a steam-pipe for conducting live steam from the boiler to the fire-box, a suitable valve, and operating mechanism whereby said valve may open automatically in case of sudden jar or accident, comprising a toggle, an adjustable supporting-shaft for same, and a movable block or weight 80 upon which said supporting-shaft rests, all operating substantially for the purpose set forth.

In testimony whereof I affix my signature in 85 presence of two witnesses.

LUCIUS E. TRUESDELL.
